UNITED STATES PATENT OFFICE.

RODNEY S. WILLARD, OF SWANTON, VERMONT.

BOX AND TUB FASTENER.

SPECIFICATION forming part of Letters Patent No. 303,775, dated August 19, 1884.

Application filed December 26, 1883. (No model.)

To all whom it may concern:

Be it known that I, RODNEY S. WILLARD, a citizen of the United States and a resident of Swanton, in the county of Franklin and State of Vermont, have invented certain new and useful Improvements in Box and Tub Fasteners; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a portion of a box provided with my improved fastener. Fig. 2 is a vertical section through the same, and Fig. 3 is a perspective view of the fastener detached.

Similar letters of reference indicate corresponding parts in all the figures.

My invention has relation to that class of fasteners for boxes, tubs, barrels, or similar packing vessels, formed by a piece of wire provided with points at its ends adapted to be driven into the parts of the vessel to be secured together; and it consists in the improved construction and combination of parts of a fastener composed of a piece of wire forming eyes at its ends, through which eyes nails or tacks pass, as hereinafter more fully described and claimed.

In the accompanying drawings, the letter A indicates the top, and B the side, of a box, which are secured together by the fastener C.

In fasteners of this kind there have been several drawbacks: First, in the fasteners made out of one piece of wire having its ends sharpened, adapting them to be driven into the parts to be secured together, the difficulty has been that where the wood is hard the points have been apt to bend, as the wire necessarily must be soft for the purpose of bending it over the edges of the parts to be connected; and, sec-

ondly, in the fasteners consisting of a strip of sheet metal having nails or tacks passing through its ends, there has been the drawback that in handling the packages the hands of the persons handling them have often been severely cut or scratched by the sharp edges of the metal strips. To avoid this I construct the fastener of a piece of wire, D, bent to form eyes E at both ends, through which eyes tacks or nails F are inserted, the eyes clamping the tacks, so that they will remain in the eyes ready for use when packed for shipment; and it will be seen that the round sides of the wire cannot injure the hands of persons handling the package secured by the fasteners, and that the nails or tacks may be of any hardness desired, adapting them to be driven into the hardest wood.

As before stated, I am aware that fasteners have been made consisting of a strip of sheet metal having the nails or tacks passing through its ends; and, also, that fasteners have been made consisting of a piece of wire having its ends sharpened, adapting them to be driven into the parts to be secured together, and forming eyes at its ends, through which tacks may be driven, assisting the sharpened ends in holding the fastening in place, and I therefore do not wish to claim these constructions, broadly; but

What I claim as a new and useful invention is—

The combination of a piece of wire having its ends bent to form eyes with two nails or tacks inserted and held in the said eyes, as and for the purpose shown and set forth.

In testimony that I claim the foregoing as my own I have hereunto affixed my signature in presence of two witnesses.

RODNEY S. WILLARD.
